SHOE

James E. Wall, North Adams, Mass., assignor to Wall-Streeter Shoe Co., North Adams, Mass., a corporation of Massachusetts

Application October 2, 1953, Serial No. 27,056

Term of patent 3½ years

(Cl. D7—7)

Fig. 1 is a perspective view of a shoe, showing my new design;

Fig. 2 is a similar view thereof showing the side opposite to that shown in Fig. 1; and

Fig. 3 is a fragmentary view showing the strap in open position.

I claim:

The ornamental design for a shoe, as shown.
